TOBACCO PIPE

Joseph Pedery, New York, N. Y.

Application July 29, 1933, Serial No. 682,751

7 Claims. (Cl. 131—12)

This invention relates to improvements in tobacco pipes. The draught or suction of such pipes is frequently impaired through the clogging which takes place at the bottom of the pipe bowl, and particularly at the junction of the bowl and the pipe stem, which clogging is due to continual accumulation of the various ingredients distilled out of the tobacco during the smoking. Those accumulated ingredients have to be frequently scraped out of the bowl, as, besides impairment of the suction, they also form hard or viscous masses which seriously vitiate the taste of the tobacco.

The principal object of the invention is to provide a tobacco pipe with improved and efficient means for remedying the above mentioned disadvantages, to ease the conveyance of the smoke through the pipe, and to prevent the distilled objectionable ingredients of the tobacco from reaching the smoker's mouth.

Another object is to provide a tobacco pipe having simplified, inexpensive, reliable, efficient, and improved means for retaining an absorbent material for remedying said disadvantages, and for readily, rapidly, and conveniently discarding and renewing said material.

Another object is to effect the improved distillation of objectionable ingredients from the tobacco within the pipe.

Other objects and advantages will hereinafter appear.

In the accompanying drawing,—

Figs. 1, 2, 3 are longitudinal cross-sectional elevations of tobacco pipes embodying the above referred improvements.

Fig. 4 is a plan view of a detail of the improvements shown in Fig. 3.

The pipe 1, Fig. 1, comprises a tobacco bowl 36 and stem portion 37, which are attachable to and detachable from each other by means of the threaded portions shown. A tablet 12 made of suitable absorbent material and provided with passageways 14 for the smoke is located in a recess 98 formed in the underside of part 36. Said tablet is retained in place against dislocation by means of a metallic band device 97, which passes under and around the sides of the tablet, and terminals 99 of the band pass through a grate 53 and bend thereover as indicated. A chamber 100 is provided in the bowl-part 37 directly under the tablet 12, and the smoke filling said chamber is led to the stem 37' through a pipe 101 extending from said stem to the upper portion of said chamber, a depression 102 in the bottom of the

chamber serving to collect objectionable precipitations.

In Fig. 2 is shown a spring band device 103 for retaining the tablet 12 in the bottom of the bowl-part 36. Said band passes around the top and sides of the tablet, and its terminals 104 pass through the opening 19 of the tobacco-bowl 36, under which they are of the bent configuration 105 shown to lockingly remain in place. Upon destruction of the absorbent tablet 12, after it is used up, the device 103 may be easily removed by bringing the bent springy terminal parts 105 toward each other.

According to the modification shown in Figs. 3, 4, the retaining device 106 resembles the one shown in Fig. 2, but it is made of a perforated metal sheet 107 which serves as a grate and rests upon the tablet 12, and legs 108 extending from said sheet are configurated and utilized similarly to the corresponding parts of the device shown in Fig. 2.

After considerable use of the pipe the absorbent tablet 12 may be renewed by detaching the bowl-parts 36, 37 from each other, demolishing the tablet material and discarding it, and withdrawing the device 97, 103, or 107, whereupon a fresh tablet may be replaced with the retaining device restored to functioning position. As the suction at the pipe-stem 37' progresses, the smoke from the tobacco is conveyed through the passageways 14 of tablet 12, which then absorbs objectionable ingredients, and then the smoke enters and fills the chamber 100, wherefrom the smoke enters the tube 101 and passes into the stem 37', as indicated by the arrows. During the smoking of the pipe the solid distilled precipitates which constitute objectionable ingredients become deposited within the depression 102, from which they may be cleaned out by the smoker during renewal of the tablet 12.

Variations may be resorted to within the scope of the invention, and portions of the improvements may be used without others.

Having thus described my invention, I claim:

1. A tobacco pipe having the combination of a two-part bowl, means to attach and detach said parts, the upper of said parts having a bottom adapted to sustain the tobacco and an opening in said bottom to permit suction therethrough, an absorbent tablet located at said bottom, and an elongated metallic band embracing said tablet horizontally and vertically as a tie having its terminal protrude through said opening to secure the tablet to said upper part.

2. A tobacco pipe having the combination of a

- two-part bowl, means to attach and detach said parts, the upper of said parts having a bottom adapted to sustain the tobacco and an opening in said bottom to permit suction therethrough, an absorbent tablet located at said bottom, and an elongated metallic band embracing said tablet horizontally and vertically as a tie having both of its terminals protrude through said opening to secure the tablet to said upper part.
- 10 3. A tobacco pipe having the combination of a two-part bowl, means to attach and detach said parts, the upper of said parts having a bottom adapted to sustain the tobacco and a plurality of openings in said bottom to permit suction there- 15 through, an absorbent tablet located at said bottom, and an elongated metallic band embracing said tablet horizontally and vertically as a tie having its terminals protrude through a pair of said openings to secure the tablet to said upper part.
- 15 4. A tobacco pipe having the combination of a two-part bowl, means to attach and detach said parts, the upper of said parts having a bottom adapted to sustain the tobacco and an opening 20 in said bottom to permit suction therethrough, an absorbent tablet located at said bottom, an elongated band embracing said tablet horizontally and vertically as a tie having its terminal pro- trude through said opening, and said terminal having means to lock it to said upper part.
- 25 5. A tobacco pipe having the combination of a two-part bowl, means to attach and detach said

parts, the upper of said parts having a bottom adapted to sustain the tobacco and an opening in said bottom to permit suction therethrough, an absorbent tablet located over said bottom, an elongated band embracing said tablet horizontally and vertically as a tie having its terminal protrude through said opening to secure the tablet to said upper part, and said band having a perforated plate integral therewith disposed on top of said tablet for its protection.

10 6. A tobacco-pipe having the combination of a two-part bowl, means to attach and detach said parts, the upper of said parts having a bottom adapted to sustain the tobacco and an opening in said bottom to permit suction therethrough, an absorbent tablet located over said bottom, an elongated band embracing said tablet horizontally and vertically as a tie having its terminal protrude through said opening, and said terminal having means to lock it to said upper part.

15 7. A tobacco pipe having the combination of a two-part bowl, means to attach and detach said parts, the upper of said parts having a bottom adapted to sustain the tobacco and an opening in said bottom to permit suction therethrough, an absorbent tablet located underneath said bottom, an elongated band embracing said tablet horizontally and vertically as a tie having its terminal protrude through said opening, and said terminal having means to lock it to said upper part.
